Primary Examiner — Darcey E Gottschalk(74) *Attorney, Agent, or Firm* — Dickinson Wright PLLC(57) **CLAIM**

The ornamental design for a bamboo / wooden container lid, as shown and described.

DESCRIPTION

FIG. 1 is a top perspective view of the bamboo / wooden container lid;

FIG. 2 is a bottom perspective view of the bamboo / wooden container lid;

FIG. 3 is a top view of the bamboo / wooden container lid;

FIG. 4 is a bottom view of the bamboo / wooden container lid;

FIG. 5 is a right side view of the bamboo / wooden container lid;

FIG. 6 is a left side view of the bamboo / wooden container lid;

FIG. 7 is a rear view of the bamboo / wooden container lid;

FIG. 8 is a front view of the bamboo / wooden container lid;

and,
FIG. 9 is a bottom perspective view of the bamboo / wooden container lid.

The broken lines in the drawings illustrate environment and portions of the bamboo / wooden container lid that form no part of the claimed design.
